UNITED STATES PATENT OFFICE.

BENJAMIN F. LINDSLEY, OF MANSFIELD, OHIO.

COMBINED FABRIC SUPPORT AND BRACE.

Application filed September 1, 1925. Serial No. 53,900.

This invention relates to a combined fabric support and brace.

It is well known to those skilled in the art pertaining to the manufacture and use of fabric for beds or the like whether consisting of cloth, connected wire links, connected link chains or the like that the fabric has a tendency to sag or sink more or less at the middle or central portion thereof by its own weight or under applied pressure below a horizontal line or plane, thereby losing firmness and elasticity and also tending to cause it to bend or give way under a load or excessive pressure.

The primary object of the present invention consists in providing a combined brace and supporting member for a fabric and attaching and supporting same from a fabric frame in close proximity to the corners thereof, so that the strain or pulling effect due to weight or pressure on the fabric will be exerted upon the most rigid portions of the fabric frame preventing the end frame members from bending at the centers and thereby shortening the distance between the end frame members, which cause the fabric to sag.

One of the objects of the present invention is to provide a fabric preferably made up of a series of wire links and yieldingly connecting same to a frame to provide a resilient fabric which will rebound or recoil when subjected to weight or pressure.

Another object of the invention is to provide a combined brace and support to reinforce, support and brace the fabric at its point of least resistance that is at or substantially in the center or the middle of the fabric.

A further object is to provide a combined support and brace which can be yieldingly supported from the fabric frame under a tension which tends to hold the combined brace and support in juxtaposition to the bottom of the support thereby sustaining and upholding the fabric and tending to prevent the yielding, sinking or giving way of said fabric at its center or point of least resistance.

A further object of the invention is to provide a combined brace and support that will tend to support and strengthen the sides of the fabric and to assist in yieldingly maintaining the plane of the fabric at the sides thereof when the fabric at the sides

is subjected to undue pressure or weight as for instance when a person sits on the side of the bed for any purpose.

A further object is to provide an elongated rectangular member which is preferably composed of two square members yieldingly connected together and which is adapted to be supported at the center of the fabric.

These and other objects are attained by the mechanism illustrated in the drawings in which:

Figure 1 is a plan view in perspective showing the fabric frame, the preferred wire fabric construction and the combined brace and support for the fabric, assembled.

Figure 2 is an enlarged plan view of one corner of Fig. 1.

Figure 3 is an enlarged side view of the rectangular member taken on the line 1—1 of Figure 1.

In the preferred embodiment of my invention I have shown a fabric composed of a series of wire link members connected together in a longitudinal and right angular relation to each other, the fabric being supported by a series of helical compressed springs which are attached to the fabric and to the fabric frame.

The invention is shown applied to a fabric made of wire links and is constructed as follows:

A frame comprising longitudinal side members 1 and 2 is provided having risers 3—3 fitted at the ends thereof. The lower portions of the risers as shown at 4 are adapted to fit the rails of a conventional bed frame. The upper portions as shown at 5 are flat and extend rearwardly and inwardly in opposed relation to each other as shown at 6.

The free inwardly extending ends of the risers are connected together by cross frame members 7 which are preferably made angular in cross section with the upper portion connected on a plane with the flat portions 5 of the risers as shown in Fig. 1.

A series of apertures 8 are provided in the upper flat leaf of the angular members. A series of compressed helical springs 9 are provided with hooked portions 10 which are inserted in the apertures 8. The opposite ends of the compressed helical springs 9 are also provided with hooked portions 11 and are connected to a series of wire links 12 formed substantially U-shaped and provided with hooked free ends 13 (which are

connected to links described hereinafter) providing intermediate connections between the helical compressed springs 9 and the body portion of link wire fabric.

8 The main body (preferred type) of fabric is constructed as follows:

The links are preferably made of one piece of wire which is turned or bent to provide eyes 14 and 15 having members 16 10 and 17 extending therefrom with the free ends bent to form hooked members 18 and 19. The eyes 14 and 15 are connected to the hooked members 13 of the intermediate link connecting members 12 and each succeeding 15 wire link member is connected in a longitudinal direction in the same manner in parallel rows.

Each row of wire links comprising the fabric is connected to the frame bars 7 at 20 each end of the frame in exactly the manner described.

It will also be observed that the link members, which are provided with two eyes and two hooks as hereinbefore described, 25 pose or comprise the main body portion of the fabric.

A series of link clips 20 are provided and connected to the eyes of the links 12 (which run in a longitudinal direction) in right angular relation thereto so as to maintain the eye links in their proper positions with relation to each other.

In order to strengthen the fabric at the sides thereof side bars 21 are yieldingly connected to the risers 6 by compressed helical springs 22.

Attention is called to the fact that the side bars are connected to the risers 6 so as to be located in a position directly in alignment with and over the top of the frame bars 1 and 2 so that the weight or pressure exerted upon the side bars will be in direct alignment with the frame bars 1 and 2 for strengthening purposes.

45 In order to hold the fabric as a whole substantially in alignment in a sidewise direction with the side bars and frame bars 1 and 2 of the fabric frame, link members 23 are connected to the eyes of the longitudinal 50 eye wire links adjacent to the side bar and to the side bars thereby maintaining the fabric in normal position lengthwise and sidewise.

The above describes the preferred embodiment of the fabric frame and means of supporting the fabric from the frame, which I prefer to use in association with the combined brace and supporting member.

The combined brace and supporting member is preferably constructed as follows:

Tie plates 24 preferably formed triangular are provided and link members 25 are connected thereto forming a member substantially square. Two of these members are 55 provided and connected together through

the medium of compressed helical coiled springs 26 to provide a yielding connection therebetween.

Supporting brace rods 27 are connected to the tie plates 24, diverging from each other in a sidewise direction and are connected to the end frame members 7 by compressed helical springs 28, one end of the springs 28 being connected near the corner of the fabric frame to the end frame bars 7 and their opposite ends being connected to the angular tie plates 24. The rods 27 are made of such length so as to be connected to the tie plates 24 and 29 under tension to exert a tension upon the supporting 80 and bracing member.

In order to further strengthen and support the sides of the fabric at an intermediate point between the supporting member and the side bars of the bed, auxiliary supporting brace rods 30 are connected at one end to the tie plates 29 and the opposite ends are connected through the medium of tie plates 31 and the helical compressed springs 32.

The auxiliary supporting brace rods are held in their normal positions by clip link members 33 which preferably are disposed to incline toward the center supporting and bracing member as shown in Fig. 1.

It will be observed as shown in Fig. 3 that the combined brace and supporting member is so constructed and assembled as to lie in juxtaposition to the fabric under tension tending to take up the slack or sag of the fabric at its weakest point or line of least resistance and further tending to support the fabric yieldingly under pressure or weight substantially on a horizontal plane.

It will further be observed that the fabric frame, fabric and combined supporting and bracing member are so associated together as to brace and reinforce each other when subjected to weight or pressure, but at all times the fabric and combined supporting and brace member are resilient and yielding in action to provide for the comfort, convenience and ease of the user of the bed or the like.

Attention is called to the fact that while the combined brace and support is preferably shown as applied to a bed frame or the like in connection with a wire fabric that application thereof can be made to couches, settees, cots or the like and the same results obtained, without deviating from the principle of the invention as described in the specification and shown in the drawings.

I claim:

In a bracing means for a bed-fabric carrying frame having end bars, a centrally arranged member comprising two series of rectangularly-arranged interconnected plates and springs connecting one series with the other, brace rods extending from the cen-

tral member diagonally of the frame, plates connected to the outer ends of the brace rods, springs connecting said last-springs connecting said plates to the end bars of the frame, an auxiliary brace rod 5 connected to each of said plates, the auxiliary rods on each side of the central member extending toward each other, plates carried by the adjacent ends of such auxiliary brace rods, springs connecting said last-named plates, and means for connecting said last-named plates to the fabric.

In testimony whereof I affix my signature.

BENJAMIN F. LINDSLEY.
